UNITED STATES PATENT OFFICE.

WARREN EARL COOPER, OF NEW YORK, N. Y.

SHAVING-CUP.

SPECIFICATION forming part of Letters Patent No. 690,101, dated December 31, 1901.

Application filed April 24, 1901. Serial No. 57,336. (No model.)

To all whom it may concern:

Be it known that I, WARREN EARL COOPER, a citizen of the United States, residing at No. 20 East Forty-seventh street, in the city, 5 county, and State of New York, have invented an Economic and Antiseptic Shaving-Cup, of which the following is a specification.

My invention relates to improvements in shaving-cups and soap-economizers; and the 10 objects of my invention are, first, to utilize the soap as part of the cup; second, to afford facilities for feeding the soap cake into the cup uniformly and conveniently; third, to expose for use only a small portion of the cake 15 of soap; fourth, to compress the portion of soap which is exposed; fifth, to make the interior of the cup present a practically unbroken surface, which can be easily and thoroughly cleansed, and, sixth, to have the bottom 20 of the cup below the aperture through which the soap is forced. I attain these objects by the mechanism illustrated in the accompanying drawings.

Figure 1 is a vertical section of the entire 25 cup. Fig. 2 is a top view of half the cup.

Fig. 3 is a bottom view of one-half of the cup.

A and A' are the sides of the cup, A being the top half or cup proper and A' being the bottom half or base.

30 B is the bottom of the cup, and a a the opening through which the soap is fed into A.

D is the feeding-tube and soap-reservoir, smooth on the inside and threaded on the out-

side. The soap cake is put into D at c c and is fed into A through the opening a a after 35 being compressed by the taper, which starts at b b. This insures a tight joint at a a and by making the surface of soap exposed more dense lessens the wear. The soap is fed into A by turning the nut C, which travels on the outside of D and communicates its motion to the soap cake by means of the plate E, which projects through the slot F and bears on C. 40

Having described my invention, what I claim as new, and desire to secure by Letters 45 Patent, is—

1. The combination of a cup A, and a feed-tube D tapered at the end projecting into the cup, and thereby forming a water-space, the tube having a movable bottom which is moved 50 up and down by a threaded ring, which winds on the outside of the feed-tube substantially as described.

2. The combination of a cup A and a feed-tube D tapered at one end through which the 55 soap passes, and is compressed as it enters the cup, the soap being moved up through the tube D by means of the movable bottom (or plate E), which is moved up and down by a threaded ring, winding on the outside of the 60 feed-tube substantially as described.

WARREN EARL COOPER.
